UNITED STATES PATENT OFFICE.

EMIL HAUSER, OF NEW YORK, N. Y.

DESIGN FOR A TABLE.

Application filed February 27, 1928. Serial No. 25,601. Term of patent 3½ years.

To all whom it may concern:

Be it known that I, EMIL HAUSER, a citizen of the United States, residing in New York city, county and State of New York, have invented a new, original, and ornamental Design for a Table, of which the following is a specification, reference being had to the accompanying drawing, forming part thereof, in which the view is a showing in perspective of a table showing my new design.

I claim:

The ornamental design for a table, as shown.

EMIL HAUSER. [L.S.]
